UNITED STATES PATENT OFFICE.

JOHN CARLSON AND MATHIAS CARLSON, OF SAMUELS, IDAHO.

PACKAGE-TIE.

1,275,130.

Specification of Letters Patent.

Patented Aug. 6, 1918.

Application filed February 27, 1918. Serial No. 219,456.

To all whom it may concern:
Be it known that we, JOHN CARLSON and MATHIAS CARLSON, citizens of Finland, residing at Samuels, in the county of Bonner 5 and State of Idaho, have invented certain new and useful Improvements in Package-Ties; and we do hereby declare the following to be a full, clear, and exact description of the invention, such as will enable others 10 skilled in the art to which it appertains to make and use the same.

This invention relates to improvements in package ties and has for one of its objects the provision of a device of this character 15 whereby the tying of knots in wrapping cord used for securing articles together and wrapping paper thereabout is entirely obviated and whereby the cord may be used on numerous occasions without mutilating 20 the same.

Another object of this invention is the provision of a member having cord fastening means whereby the cord may be secured about the package without tearing the same, 25 and further a clamping member adapted to secure the cord to the member.

A further object of this invention is the provision of a package tie of the above stated character, which shall be simple, durable and efficient, and which may be manufactured and sold at a comparatively low 30 cost.

With these and other objects in view as will become more apparent as the description proceeds, the invention consists in certain novel features of construction, combination, and arrangement of parts as will be hereinafter more fully described, and claimed.

40 For a complete understanding of our invention, reference is to be had to the following description and accompanying drawing, in which:

Figure 1 is a perspective view of a package tie constructed in accordance with my invention.

Fig. 2 is a plan view of the same with the clamping member in an open position.

Fig. 3 is a bottom plan view of the package tie.

Fig. 4 is a longitudinal sectional view of the same.

Fig. 5 is a transverse sectional view, illustrating the manner of securing the cord to 55 the member.

Referring in detail to the drawing, the

numeral 1 indicates an attaching member constructed from metal or any other material suitable for the purpose and has secured to its top face an attaching clip 2. The 60 attaching clip 2 is secured to the member 1 by means of a rivet or like fastener 3 and the clip has each end spaced from the member 1 as illustrated in Fig. 5 so as to receive the binding cord of a package.

A substantially S-shaped attaching clip 4 is secured to the bottom face of the member 1 by the rivet 3 and has each end spaced from the member 1 so as to receive and grip the cord. A clamping member 5 is hinged 70 to one end of the member 1 as illustrated at 6 and has formed on its free end a pair of spaced lugs 7. The clamping member 5 is adapted to be swung over the member 1 and the spaced lugs 7 engaged by a link 8 carried 75 by one end of the member 1 so that the member 1 and clamping member 5 are firmly secured together. The members 1 and 5 are of the same shape so as to provide a compact and convenient arrangement of parts.

In operation, a cord 9 is passed under one of the ends of the attaching clip 4 and then about a package 10. After the cord passes around the ends of the package 10, it is inserted under the other end of the attaching clip 4 and then passed under each end of the attaching clip 2. The other end of the cord is then passed around the sides of the box and over the member 1 and under one end of the attaching clamp 2 thus tightly 90 securing the cord 9 about the package 10. The member 5 is then swung downwardly upon the member 1 and the link 8 placed over the lugs 7 which forces the ends of the attaching clip 2 downwardly against the 95 member firmly securing the ends of the cord.

While we have shown and described the preferred embodiment of our invention, it will be understood that minor changes in construction, combination and arrangement 100 of parts may be made without departing from the spirit and scope of the invention as claimed.

Having thus described our invention, what we claim is:

1. A package tie comprising a plate, an attaching clip secured to the bottom face of said plate and adapted to receive a cord after being passed once about an article, a second attaching clip secured to the top face 110 of the plate and adapted to receive the ends of the cord after being passed about a pack-

age a second time, and a clamping member hinged to the plate and adapted to be swung in engagement with the second named clip to compress the same against the member for 5 clamping the ends of the cord, spaced lugs formed on said clamping member and a link carried by said plate for engagement with the lugs.

2. A package tie comprising a plate, an 10 attaching clip secured to the bottom face of said plate and adapted to receive the cord after being passed once about an article, a second attaching clip secured to the top face of the plate and adapted to receive the ends 15 of the cord after being passed about the package a second time, and clamping means

adapted to engage the second named clip to compress the same against the member for clamping the ends of the cord.

3. A package tie comprising a plate, means 20 on one face of said plate for gripping a cord, means on the other face of the plate for gripping the cord a second time, and means compressing the first named gripping means.

In testimony whereof we affix our signatures in presence of two witnesses.

JOHN CARLSON.

MATHIAS CARLSON.
